TOY DOG OR SIMILAR ARTICLE

Helen H. Malsed, Seattle, Wash.

Application February 28, 1956, Serial No. 40,397

Term of patent 14 years

(Cl. D34—15)

Figure 1 is a perspective view of a toy dog or similar article showing my new design in expanded position, and Figure 2 is a perspective view thereof in contracted position.

I claim:

The ornamental design for a toy dog or similar article, as shown.
